THOMAS W. SUDDARD, OF TWO RIVERS, WISCONSIN, ASSIGNOR TO THE HAMILTON MANUFACTURING COMPANY, OF TWO RIVERS, WISCONSIN, A CORPORATION OF WISCONSIN.

LETTER-BOARD.

1,034,163.

Specification of Letters Patent. Patented July 30, 1912.

Application filed February 16, 1912. Serial No. 678,043.

To all whom it may concern:

Be it known that I, THOMAS W. SUDDARD, citizen of the United States, residing at Two Rivers, in the county of Manitowoc 5 and State of Wisconsin, have invented a certain new and useful Improvement in Letter-Boards, of which the following is a full, clear, concise, and exact description, reference being had to the accompanying 10 drawings, forming a part of this specification.

My invention relates to letter boards, which are devices for receiving type matter before or after its location within chases, 15 the letter boards being so constructed as to permit the type matter readily to be transferred thereto from galleys. The letter boards are individually supported by cleats or runs in a cabinet so that they may be 20 readily drawn in and out, somewhat in the manner of drawers. To the end that the boards may be approached as closely as practicable, allowing sufficient clearance for the type and permitting of access to the 25 various boards so that they may be individually withdrawn from their containing cabinet, side rails are provided for the boards whose top and bottom faces lie in planes between which the board proper is 30 disposed. In order to prevent the type matter from being pushed over the back edge of the board a back rail is provided for the board. In order to afford a resting place for the galleys the board is provided 35 with a lip at the front, this lip being sufficiently depressed so that the type supporting level of the galley and the type supporting level of the letter board may be substantially coincident to enable the type 40 readily to be pushed from the galley to the letter board. In order to enable the letter board to be withdrawn from its normal position in the cabinet containing the same, the galley supporting lip is provided with a 45 formation beneath the same which may readily be engaged by the fingers. Hitherto the board, the rails and the combined galley supporting lip and finger holding formation have been made in separate parts 50 and afterward assembled into the complete structure.

It is the object of my invention to reduce the number of parts entering into the complete letter board structure and while I prefer to make the entire structure out of an

integral piece of suitable material, I do not wish to be limited to this precise embodiment of my invention.

In practicing my invention I employ sheet material for making the letter board structure, this material being desirably in the form of sheet metal such as steel which is suitably operated upon by proper die mechanism to form the letter board structure in accordance with my invention. 60 65

I will explain my invention more fully by reference to the accompanying drawing showing the preferred embodiment thereof and in which—

Figure 1 is a plan view showing a letter board as constructed in accordance with the preferred embodiment of the invention; Fig. 2 is a sectional view on line 2 2 of Fig. 1; and Fig. 3 is a sectional view on line 3 3 of Fig. 1, Figs. 2 and 3 being on an enlarged scale as compared with Fig. 1. 70 75

Like parts are indicated by similar characters of reference throughout the different figures.

The letter board proper 1 is desirably made of a sheet of steel whose side margins are first upwardly deflected at 2, then laterally and outwardly deflected at 3, thereafter downwardly deflected at 4, inwardly deflected at 5, upwardly deflected at 6, and inwardly deflected at 7, the portions 7 underlying the main letter board element 1 and contacting therewith, the main portion 1 of the letter board being desirably electrically welded or otherwise secured in fixed relation with the portions 7. The portions 2, 3, 4, 5 and 6 upon each side of the main part 1 of the letter board structure constitute side rails which may rest upon the runs provided in a letter board receiving cabinet, the lower portions of these side rails serving to maintain proper clearance between the letter boards which are usually arranged in vertical tiers. The rear margin of the sheet out of which the structure is made is upwardly turned to provide an upwardly extending back rail 8 to prevent the type matter from being pushed off the board after it has been placed thereupon. The forward portion of the structure is slightly downwardly deflected at 9 and forwardly continued to constitute a lip 10 on which to rest the galleys. This lip 10 is provided with a downward continuation 11, and the continuation 11 is desirably rear- 80 85 90 95 100 105 110

wardly continued at 12 to afford a finger hold to enable the letter board readily to be caught by the hand when it is desired to withdraw it from its containing cabinet.

5 While I have herein shown and particularly described the preferred embodiment of my invention, I do not wish to be limited to the precise details of construction shown as changes may readily be made without departing from the spirit of my invention.

10 Having thus described my invention I claim as new and desire to secure by Letters Patent the following:

1. A letter board including a single piece 15 of sheet material in its construction which is shaped to include the type material supporting portion of the letter board, the side rails of the letter board that are extended above and below said type material supporting portion, a forwardly extending depressed galley supporting lip, a downward and rearward extension of the galley supporting lip and an upwardly extending back rail.

25 2. A letter board including a single piece of sheet material in its construction which is shaped to include the type material supporting portion of the letter board, the side rails of the letter board that are extended 30 above and below said type material supporting portion, a forwardly extending depressed galley supporting lip, and a downward and rearward extension of the galley supporting lip.

35 3. A letter board including a single piece of sheet material in its construction which is shaped to include the type material supporting portion of the letter board, the side rails of the letter board that are extended 40 above and below said type material supporting portion, a forwardly extending depressed galley supporting lip, and a downward extension of the galley supporting lip.

45 4. A letter board having side rails that are extended above and below the type material supporting portion of the board and including a single piece of sheet material in its construction which is shaped to include the type material supporting portion of the letter board and a forwardly extending depressed galley supporting lip.

55 5. A letter board having side rails that are extended above and below the type material supporting portion of the board and including a single piece of sheet material in its construction which is shaped to include the type material supporting portion of the letter board, a forwardly extending depressed galley supporting lip, and a downward and rearward extension of the galley supporting lip.

65 6. A letter board including a single piece of sheet material in its construction which is shaped to include the type material supporting portion of the letter board, the side

rails of the letter board that are extended above and below said type material supporting portion, a forwardly extending depressed galley supporting lip, and an upwardly extending back rail.

70 7. A letter board including a single piece of sheet material in its construction which is shaped to include the type material supporting portion of the letter board, the side rails of the letter board that are extended above and below said type material supporting portion, a forwardly extending galley supporting lip, a downward and rearward extension of the galley supporting lip and an upwardly extending back rail.

75 8. A letter board including a single piece of sheet material in its construction which is shaped to include the type material supporting portion of the letter board, the side rails of the letter board that are extended above and below said type material supporting portion, a forwardly extending galley supporting lip, and a downward and rearward extension of the galley supporting lip.

80 9. A letter board including a single piece of sheet material in its construction which is shaped to include the type material supporting portion of the letter board, the side rails of the letter board that are extended above and below said type material supporting portion, a forwardly extending galley supporting lip, and a downward and rearward extension of the galley supporting lip.

85 10. A letter board including a single piece of sheet material in its construction which is shaped to include the type material supporting portion of the letter board, the side rails of the letter board that are extended above and below said type material supporting portion, a forwardly extending galley supporting lip, and an upwardly extending back rail.

90 11. A letter board having side rails that are extended above and below the type material supporting portion of the board and including a single piece of sheet material in its construction which is shaped to include the type material supporting portion of the letter board, a forwardly extending depressed galley supporting lip, and a downward extension of the galley supporting lip.

95 12. A letter board having side rails that are extended above and below the type material supporting portion of the board and including a single piece of sheet material in its construction which is shaped to include the type material supporting portion of the letter board and a forwardly extending galley supporting lip.

105 13. A letter board having side rails that are extended above and below the type material supporting portion of the board and including a single piece of sheet material in its construction which is shaped to include

- the type material supporting portion of the letter board, a forwardly extending galley supporting lip, and a downward and rearward extension of the galley supporting lip.
- 5 14. A letter board having side rails that are extended above and below the type material supporting portion of the board and including a single piece of sheet material in its construction which is shaped to include
- 10 the type material supporting portion of the letter board, a forwardly extended galley supporting lip, and a downward extension of the galley supporting lip.
- In witness whereof, I hereunto subscribe my name this 9th day of February A. D., 1912.

THOMAS W. SUDDARD.
